DESIGN FOR A PERFUME BOTTLE OR ANALOGOUS ARTICLE

Warren Carter, Los Angeles, Calif., assignor to
S & G Gump Company, a corporation of California

Application April 16, 1948, Serial No. 145,766

Term of patent 7 years

(Cl. D58—8)

To all whom it may concern:

Be it known that I, Warren Carter, a citizen of the United States, residing in the city of Los Angeles, county of Los Angeles and State of California, have invented a new, original, and ornamental Design for a Perfume Bottle or Analogous Article, of which the following is a specification, reference being had to the accompanying drawing, forming a part thereof.

In the accompanying drawing:

Fig. 1 is a perspective view of a perfume bottle or analogous article embodying my new design;

Fig. 2 is a side elevational view of the same; and

Fig. 3 is a top plan view of the same.

I claim:

The ornamental design for a perfume bottle or analogous article, substantially as shown.

WARREN CARTER.
